CLAIM

The ornamental design for a storing and dispensing apparatus, as shown and described.

DESCRIPTION

FIG. 1 is a perspective view of a storing and dispensing apparatus showing my new design;
 FIG. 2 is a top plan view thereof;
 FIG. 3 is a front elevational view thereof;
 FIG. 4 is a left side elevational view thereof, the right side being a mirror image; and,
 FIG. 5 is a rear elevational view thereof.
 The broken line showing of cans in FIGS. 3 and 4 is for illustrative purposes only and forms no part of the claimed design.
 The bottom is plain and unornamented.
